CLAIM

The ornamental design for a tape dispenser, substantially as shown and described.

DESCRIPTION

FIG. 1 is a perspective view of a tape dispenser showing our new design;

FIG. 2 is a top plan view thereof;

FIG. 3 is a right side elevational view, the left side being a mirror image thereof;

FIG. 4 is a bottom plan view thereof;

FIG. 5 is a front elevational view thereof;

FIG. 6 is a rear elevational view thereof;

FIG. 7 is a perspective view of a second embodiment of a tape dispenser showing our new design;

FIG. 8 is a top plan view of the dispenser of FIG. 6;

FIG. 9 is a right side elevational view of the dispenser of FIG. 6;

FIG. 10 is a bottom plan view of the dispenser of FIG. 6;

FIG. 11 is a front elevational view of the dispenser of FIG. 6; and

FIG. 12 is a rear elevational view of the dispenser of FIG. 6.
